BLOCK GREASE TESTING APPARATUS

Herschel G. Smith, Wallingford, Pa., assignor to
 Gulf Oil Corporation, Pittsburgh, Pa., a corporation of Pennsylvania

Application March 12, 1945, Serial No. 582,401

6 Claims. (Cl. 73—10)

This invention relates to block grease testing apparatus useful for determining and comparing the rate of consumption or wearing characteristics of blocks of different hard greases when subjected to the rubbing action of a smooth hard surface under controlled conditions of temperature, feeding pressure and surface speed etc., whereby a reliable indication of the wearing characteristics of the grease that may be expected from its use in actual service may be obtained.

Block or hard greases are of definite utility in many of the heavy industries where they perform a special lubrication service. They are useful for instance, in the lubrication of the journals of steel mill rolls, paper mill rolls, railway driving journals and in the rod cup bearings of locomotives where bearing temperatures are high. They are also widely used in the lubrication of heavy equipment, particularly on the large open bearings of such equipment where the use of soft greases is considered unacceptable. In many instances the use of block grease is preferred over oils or soft greases by reason of the fact that a block grease, suitable to the purpose, provides uniform lubrication over long periods of time with less labor, attention and trouble.

Block greases vary widely in their compositions and in their methods of compounding and processing, depending mainly on the specific purposes for which they are intended to be used. In general, however, they are characterized by being relatively hard, molded products usually in the form of blocks or sticks which retain their shape not only at atmospheric temperatures but at temperatures above actual operating temperatures encountered in use. In addition, the ideal block grease presents an oily, or slick, and non-adhesive surface to the bearing on which it is used and should wear away, due to rubbing or drag on the bearing, only as fast as it is necessary to provide uniform and adequate lubrication. The achievement of such a block grease for a specified lubrication service is somewhat of a rarity and is now accomplished largely through hit or miss experimentation rather than by logical, systemized, controlled testing and examination.

Certain empirical tests such as consistency or penetration tests, and melting or dropping point tests have been applied to block greases and are useful for measuring apparent hardness and melting point respectively, but these tests taken singly or together are not adequate or sufficiently reliable in their results to render possible accurately predicting the rate of feed or block con-

sumption of the grease under different conditions of use. Further, the results of these tests are not reliable or conclusive guides in duplicating wear performance values with different greases made by other methods of compounding.

In use, block grease is generally placed in a holder on the bearing to be lubricated and the block is held in contact with the moving surface by spring pressure, or by simply its own weight, i. e. gravity feed. In such use, experience has shown that the serviceability and consumption rate of the block is affected not only by the melting point and consistency of the grease but also upon its jell properties and upon the "drag" or tendency of the grease to adhere to the bearing and be pulled or torn away from the block.

In addition the structure of the grease is important both as regards stability of the compound and its strength or resistance to deformation when shaped or molded. The grease must be stable in that no deleterious changes occur in its composition either in the body portion of the block or at the surface where it contacts with the hot moving metal part of the bearing. In some cases greases that at first appear satisfactory will develop leaching of oil, oxidation and other effects associated with elevated temperatures and ageing. These effects are sometimes accelerated by conditions surrounding the use of the grease. The grease should not be too hard or "non-wearing" lest insufficient lubrication and consequent serious damage result; and yet it should not become too soft or pasty in use or there will be too much lubrication, grease will be wasted, and the life of the block will be short. In this latter case there is also danger from inadequate lubrication unless special care and attention is given to renewal of the block. If the grease is too soft it may spatter and be thrown clear of the bearing to contaminate products processed by the machine and require excess labor in keeping the machine clean.

It is an object of the present invention to provide a test apparatus useful for research and control of the wear performance values or characteristics of blocks of hard grease under conditions closely paralleling conditions of use of the grease in actual service.

A further object of the present invention is to provide means for determining the rate of feed or block consumption of block grease at different bearing temperatures which rate of feed will be fairly indicative of the wearing characteristics or life of a block of the grease when subjected to similar temperatures in actual use.

A further object of the invention is the provision of apparatus for measuring the wear resistance of a block of block grease based upon its "drag" characteristics, its jell properties and its use melting point, which apparatus shall be extremely sensitive to small changes in these characteristics and in which error arising from reworking of the grease is substantially avoided.

A further object of the invention is the provision of apparatus useful for accurately estimating the flow, drag and jell stability values of a block grease as such values affect its wear characteristics when lubricating bearings at different feed pressures.

A still further object of the invention is the provision of such a test apparatus which shall be simple in construction and operation, inexpensive to build, accurate and reliable in use and which will enable accelerated testing of the consumption characteristics of a number of blocks of hard grease simultaneously.

The above and other objects are accomplished by the apparatus of the present invention as will be apparent from the following description and accompanying drawings in which there is illustrated more or less diagrammatically, a preferred embodiment of the invention.

In the drawings,

Fig. 1 is a top plan view of a preferred form of apparatus of the present invention.

Fig. 2 is a front view partly in elevation and partly in section.

Fig. 3 is an end view in elevation of the apparatus; and

Fig. 4 is a detail vertical sectional view of the rack for supporting the blocks of grease in test position on the machine.

Referring to the drawings and more especially to Figs. 2 and 3, the base of the apparatus consists of a heavy flat rectangularly shaped member 5 of wood or metal or the like, at each end of which is mounted a pair of spaced, upright, angle iron supports or standards 6 and 7, respectively. Trunnioned between the supports in bearings 8 and 9 respectively is a closed end, smooth, machine surfaced hollow cylinder or drum 10, adapted to be rotated by means of an electric motor 11. The motor is mounted on the base plate as shown and provided with a pulley 12 which drives a belt 13 in engagement with a second pulley 14 keyed to trunnion 15 of the cylinder.

To provide for heating the cylinder and for maintaining it at any desired constant temperature a heating fluid such as oil, water or steam is circulated through the cylinder. For this purpose cylinder trunnions 15 and 16 extend slightly into the cylinder as shown, and are hollow for receiving fluid conducting tubes 17 and 18 respectively. The trunnions are welded as at 19 and 20 respectively, to the end walls of the cylinder to provide sealed or leak proof joints at these points and the outside vertical faces of the welds are machined smooth to serve as both thrust bearings and centering means for the cylinder. Tubes 17 and 18 are welded to the trunnions where they enter and leave for providing sealed fluid proof connections at these points. The outer end of each tube terminates in packing boxes or glands 21 and 22, respectively, in accurate alignment with the axis of the cylinder. Opposite the terminal ends of tubes 17 and 18 the packing boxes are threaded to receive pipes 23 and 24, respectively, for conducting heating fluid from a suitable source not shown to and away from the

cylinder. Tube 17 is curved outwardly inside the cylinder as at 25 and terminates at a point closely adjacent the cylinder wall to provide for efficient circulation of the heating fluid. Advantageously pipe 24 may serve to deliver heating fluid to the cylinder while pipe 23 serves to carry it away.

Positioned immediately above cylinder 10 is a grease block rack consisting of a pair of side rails 26 connected together at their ends by strap like members 27. Between the side rails but preferably secured thereto as by welding are a plurality of vertically disposed rectangular shaped, open ended metal boxes forming metal walled compartments for receiving the blocks of grease to be tested. The bottom edges of the compartments are arranged to conform to the curved surface of the cylinder. The rack is adjustable vertically to position the lower edges of the holders a desired distance above the surface of the cylinder. This is accomplished by positioning the side rails 26 of the rack in open ended slots or guide ways 29 in the ends of standards 6 and 7 and permitting them to rest upon vertically adjustable stops or guide plates 30. Stops 30 are also provided with elongated slots through which bolts 31 pass for clamping the plates in the desired vertical position on the standards. Thus, it may be seen that the rack is adjustable vertically and may be removed from the apparatus by simply lifting.

The rack is provided with four block grease compartments which are alike in size and shape and are substantially square or cubical in shape. Each compartment is adapted to receive a block of grease, as shown, of a size to form a sliding fit within the compartment. For positively feeding or forcing the grease into contact with the cylinder, iron or lead weights 32 of definite value and of a size to fit loosely within the compartments are placed in the compartments on top of the grease. For convenience in handling, the weights are provided with circular openings 33.

Considering the rotation of cylinder 10 in Fig. 3 to be counter-clockwise as indicated by the arrow, standards 6 and 7 at the ends of the cylinder are provided with cylinder scraper blade supports disposed as shown at 34 and 35, respectively. Adjustably secured to the scraper supports as by means of threaded stud bolts 36 brazed to the supports are scraper blade bed plates 37. The plates may be adjusted toward or away from the cylinder and locked in position by means of nuts 38. The scraper blades shown at 39 consist of thin narrow strips of brass or bronze of spring like temper, rigidly clamped to the scraper blade supports by means of cover plates 40 and winged clamping screws 41. The blades are slightly longer than cylinder 10 so that they extend a short distance beyond the ends of the cylinder, and are adjustable into scraping engagement with the cylinder by loosening clamping screws 41 and moving the blades forward or backward.

As shown, two scraper blades and scraper blade support assemblies are used, positioned advantageously a little less than 180° apart. The purpose of the blades is to remove as much of the grease as possible from cylinder 10 in order to prevent any substantial re-working of the grease.

Positioned beneath cylinder 10 to catch the grease removed by the scrapers is a pan 42. The pan simply rests on the base 5 of the apparatus

and is arranged for a loose sliding fit between the standards.

In use, steam or hot water at the desired temperature is circulated through the cylinder and the cylinder rotated for a period of about 10 minutes or until the surface temperature of the cylinder reaches equilibrium. One to four sample blocks of grease trimmed to size are carefully weighed and then placed in the compartment in the grease rack. A weight of suitable value is next placed on top of the grease in each compartment and the machine operated at a definite speed for a certain length of time, say, 2 hours. The machine is then stopped, the blocks of grease removed and weighed and their loss in weight determined. The grease consumption may be expressed in grams per hour as calculated by dividing the loss in weight of the block in grams by the number of hours during which the block is in contact with the rotating cylinder. The simultaneous testing of two or more blocks of grease under identical conditions of temperature, time and cylinder surface speed, etc., enables quick and accurate comparison of the block consumption characteristics of different greases.

If desired, the machine may be operated at different temperatures with the same grease and a curve plotted to show the different consumption values of the grease at these different temperatures. The change in slope of the grease consumption curve may be sharp or gradual as covering a small or large temperature range. Such curves are particularly useful for determining or predicting the service performance of a block of grease that is to lubricate machinery whose temperature varies markedly.

With a set of grease consumption data for a particular range of temperatures one is able to tell at a glance just about how the grease will perform under a prescribed set of conditions.

The test apparatus described is simple in construction and operation and inexpensive to build. It provides a ready guide or gage useful for research and control of the wear performance values of block greases and gives results as regards block consumption which are closely co-ordinate with results obtained in actual practice.

What I claim is:

1. A block grease testing machine comprising a hollow cylindrical drum, means for rotating said drum, means for circulating a heating fluid through the drum for maintaining the temperature of the drum substantially uniform and constant, means for supporting a plurality of blocks of block grease in juxtaposition adjacent the drum and in rubbing engagement with the cylindrical surface of the drum, and a scraper blade in scraping engagement with the drum adapted to substantially completely remove grease from said surface, whereby reworking of the grease on subsequent rotation of the drum is avoided.
2. A machine for testing the consumption characteristics of blocks of block grease, comprising a smooth cylindrical surface rotatable about its longitudinal axis, means for maintaining said surface at a substantially uniform, constant temperature, holding means for supporting a plurality of blocks of block grease over said surface such that said blocks are positioned for rubbing engagement with the surface, weights adapted for insertion in said holder on top of the grease for maintaining a constant feeding pressure on the grease with respect to said surface, and a plurality of thin flexible scraper blades for said surface adapted to maintain the surface of the cylinder approaching said blocks during rotation of the cylinder substantially free of grease, whereby reworking of the grease is avoided.
3. The subject matter of claim 2 wherein said holding means for the blocks of grease is adjustable toward and away from the cylindrical surface.
4. The subject matter of claim 2 wherein said flexible scraper blades are adjustable toward and away from the cylindrical surface.
5. The subject matter of claim 2 wherein said grease block holding means is removable from the machine by simply lifting.
6. The subject matter of claim 2 wherein the cylindrical surface is maintained at a uniform, constant temperature by contact with a circulating heating fluid.
